United States Patent Office

Des. 180,227

Patented May 7, 1957

180,227

AUTOMOBILE DOOR

Virgil M. Exner, Birmingham, Mich., assignor to Chrysler Corporation, Highland Park, Mich., a corporation of Delaware

Application July 26, 1955, Serial No. 37,125

Term of patent 7 years

(Cl. D14—6)

FIG. 1.

FIG. 2.

FIG. 3.

Fig. 1 is a front elevational view of an automobile door, showing my new design;

Fig. 2 is a front elevational view thereof on a larger scale;

Fig. 3 is a side elevational view of the automobile door taken on the line 3—3 of Fig. 2; and

Fig. 4 is a vertical sectional view of the door taken on the line 4—4 of Fig. 2.

The broken line showing in the drawing figures is for illustrative purposes only.

I claim:

The ornamental design for an automobile door, substantially as shown and described.
